HUMIDIFIER BOILER

Edward W. Bottum, Detroit, Mich., assignor to
 Skuttle Manufacturing Company, Detroit,
 Mich., a corporation of Michigan

Application March 16, 1949, Serial No. 81,809

10 Claims. (Cl. 122—20)

1

This invention relates to a vaporizing apparatus for discharging vapor into a gaseous medium and more particularly, but not exclusively, to a humidifier in which water or other vapor may be discharged into an air mass in quantities controlled by variations in the calorific output of a heating unit.

It is well known that air heated by a conventional furnace, or other heating unit, has a relatively low humidity which is both uncomfortable and unhealthy. Many humidifying devices for heating units have been previously suggested and used. For the most part, the devices have been incapable of providing the necessary degree of humidification for the air and also have been incapable of rapidly and suddenly changing in response to changes in the heating output of the heating unit. For these reasons, the prior humidifying devices have proven unsatisfactory.

Most frequently the conventional humidifying apparatus employed consisted of an open pan or receptacle of water positioned either within the heated rooms or within the air chambers of the furnace itself. Humidifiers of this type are not satisfactory for use under many conditions. Due to the high heat of vaporization of water, substantial heat is removed from the surrounding air by this type of humidification. Various methods for increasing the water vaporization in water pans or receptacles has been employed such, for example, as increasing the effect of vaporization surface of the water, by the use of absorbent fins or plates, or by increasing the temperature of the water in the receptacle. While these methods have increased the vaporization rate, the increase has in some instances been insufficient to provide the desired amount of humidification; heat is still absorbed from the surrounding air to evaporate the water; and in addition, the amount of humidity supplied to the air cannot be accurately controlled to compensate for sudden changes in the heat output of the furnace. In the prior humidifiers wherein the water is heated, such as by heating coils, a substantial quantity of water must be kept in the receptacle at all times in surface contact with the heated air. For this reason the water cannot be heated or cooled quickly to suddenly change the vaporization rate and consequently compensate for sudden changes in the temperature or volume of the heated air.

With the humidifying apparatus of the present invention, water is metered to a steam chamber in proportion to the evaporation rate within the chamber, which in turn is in proportion to

2

the heat of the gases in the furnace flue. The apparatus includes a water reservoir positioned outside the heated portion of the furnace, a heat transfer unit positioned within a heated portion of the furnace, preferably within the furnace flue, and one or more absorbent plates extending from the water in the reservoir into a steam chamber provided in the heat transfer unit. In operation, no liquid water is present within the steam chamber except that which is present on the surface of the absorbent material. The rate of flow of water to the chamber is thus dependent solely upon the rate of vaporization of the water from the surface of the absorbent plates. Any number of absorbent plates may be employed to provide a sufficient flow for maximum vaporization rates within the chamber.

The steam generated in the steam chamber is directed into the heated air by any suitable means. 20 If desired, forced circulation may be employed such as by the use of a centrifugal blower to force the steam from the chamber into the heated room, or if desired, into the furnace hot air ducts.

25 Prior humidifiers which are dependent upon currents of heated air to absorb the moisture and carry it into the area to be heated, are of no value in heating systems utilizing hot water or steam as the heat exchanging medium in radiators or the like located in the area to be heated. The efficiency of such heating systems is well known but the difficulties in providing suitable humidification in areas heated thereby have reduced the demand for such heating systems.

30 It is therefore an object of the present invention to provide a vaporizing apparatus which may be used with any type of heating system to supply and discharge vapor into the air in an area to be heated in quantities necessary for maintaining a uniform and satisfactory predetermined volumetric concentration of the vapor which will vary automatically with the heat output of the heating system.

35 It is another object of this invention to provide a humidifying apparatus which will supply water in vaporized state to heated and relatively dry air and will automatically and quickly vary the water vapor output to the air in accordance with the heat output from the furnace.

40 Still another object is to provide an apparatus which is sensitive to small variations in the heat output of the furnace whereby a relatively constant humidification of the air may be obtained.

45 Another object of the invention is to provide a humidifying apparatus in which only a small

quantity of liquid water is present within the steam chamber on the surface of the absorbent plates in order that the steam output of the apparatus may vary rapidly with small temperature variations within the chambers.

Another object of this invention is to provide a humidifying apparatus having a means to force the flow of water vapor from the steam chamber into the relatively dry air of the area to be heated.

Other objects of this invention will appear in the following description and appended claims, reference being had to the accompanying drawings forming a part of the specification wherein like reference characters designate corresponding parts of the several views.

In the drawings:

Fig. 1 is a front elevation of the humidifying apparatus embodying the features of the present invention and showing the water chamber in section and also showing a portion of the cover plate broken away for clarity;

Fig. 2 is a sectional view taken substantially on the line 2-2 of Fig. 1; and

Fig. 3 is a reduced fragmentary sectional view showing a modification of the humidifying apparatus of the present invention.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The humidifying apparatus 10 of the present invention is shown in Figs. 1 and 2 of the drawings in assembled relation with an assembly plate 12 and a water chamber 13 having a standard type float control 14 therein. The humidifying apparatus 10 comprises essentially the heat transfer unit 15 having a steam chamber 16 therein, a water reservoir 17 and a plurality of absorbent plates 18 extending from the water 19 in the reservoir into the steam chamber 16, provided in the heat transfer unit.

As shown in the drawings, a unitary hollow member forms both the rectangular heat exchanger unit, including the fins 20 and the cylindrical body portion 21 of the water reservoir. The hollow member is formed of a non-corrosive heat conducting material such as aluminum and is preferably of a cast construction. One end of the steam chamber opens into the water reservoir, but is positioned above the normal level of the water within the reservoir. The water is carried by capillary action within the absorbent plates 18 from the reservoir 17 into the steam chamber and any excess water in the chamber such as by condensation of the water vapor will flow by gravity back into the reservoir 17.

The open end of the body portion 21 of the reservoir 17 is provided with a pair of transverse flanges 22. A cover plate 23 encloses the open end of the body portion and is removably secured thereto by a pair of screws 24, threaded into the transverse flanges 22. The cover plate is provided with an annular flange 25 which seats on the outer periphery of the body portion 21. An annular gasket 26 is positioned within the flange 25 and seals the open end of the water reservoir.

An outlet port 27 is formed in a threaded boss 28 located in the top of the body portion 21 and

communicates with the steam chamber. Vapor is led from the outlet port 27 through the conduit 27a which discharges into any desired area. The threaded boss 28 is provided with a threaded nut 29 which with the packing 29a provides a vapor tight connection with the conduit 27a. The water chamber is also provided with a downwardly depending water inlet port 30 having an opening in one end thereof connected with the conduit 31 extending from the water chamber 13. The opposite end of the water inlet port and also the heat exchanger unit 14 are each provided with a threaded plug 32.

The absorbent plates 18 are generally L-shaped and are supported vertically within the steam chamber 15 and have the short arm portions 18a extending below the liquid level line 19. The plates are preferably formed of compressed glass fibers or the like having a porous structure providing a plurality of capillary spaces in which the liquid may rise by capillary attraction from the reservoir 17 into the chamber 16. In operation the liquid on the surface of the absorbent plates 18 is evaporated by the heat given up by the heat conducting walls of the heat exchanger and is discharged into the relatively dry air through the outlet port 27. As shown in the drawings, six plates have been found suitable for most humidifying purposes. However, any number of absorbent plates 18 may be employed in the apparatus as desired depending upon the liquid to be evaporated, the extent of dehydration and the volume of the air to be humidified.

The water level in the water reservoir is controlled and maintained by the water level in the water chamber, which in turn is controlled by the float control mechanism 14. The latter mechanism includes a plunger valve 33 for controlling the flow of water into the water chamber and is operated by the float 34 through the connecting arm 35 and the link 36. The arm 35 is pivoted to a rod 37 which in turn is adjustably supported on the U-shaped bracket 38 by the thumb nut 39. The bracket 38 has an end portion 40 rigidly secured to the adjacent inner wall of the water chamber.

The float 34 may be manually operated to open the valve 33 by the float control arm 41. The latter is supported by the water chamber cover 42 and is pivotally secured intermediate the ends of the control arm 41 to the angle bracket 43 mounted on the cover.

The float control arm 41 is provided with a handle portion 44 extending through a longitudinal slot therein and the lower end of the control arm is twisted to provide a transverse portion 45 which is adapted to engage the float arm 35 upon upward movement of the handle portion of the control arm. An overflow pipe 46 is also provided in the water chamber 13.

The assembly plate 12 is shown comprising a pair of plates, each plate of which has one end secured as at 47 to the body portion 21. The other end 48 of each plate is curved inwardly to conform to the external contour of the metal flue of any conventional furnace.

A modification of the invention is shown in Fig. 3 in which a centrifugal fan 49 is mounted on the end plate 50 secured to the water reservoir 17. The centrifugal fan is driven through the shaft 51 by the motor 52 secured by any suitable means on the outside of the cover plate 50. The latter is provided with an annular air inlet opening 53 in the low pressure area adjacent the axis of the shaft.

With the present apparatus, the heat exchanger, preferably extending into the flue of the furnace, is heated by the combustion gases within the flue in proportion to the temperature of the combustion gases. The heat generated within the vaporization chamber therein vaporizes the liquid on the surface of the absorbent plates and discharges the vapor into the area to be heated in quantities necessary for maintaining a uniform and satisfactory predetermined volumetric concentration of the vapor. The quantity of vapor generated in the vaporization chamber will thus vary automatically with the heat output of the heating system.

The vaporizing chamber is positioned above and opens into the water reservoir whereby any excess liquid present within the vaporizing chamber, such as due to condensation, will immediately return by gravity flow to the reservoir. For this reason, the only liquid present within the chamber is the small amount present within the absorbent plates and on the surfaces thereof so that the apparatus will operate quickly to vary the vapor output to the air in accordance with the heat output of the furnace and is sensitive to small variations in the heat output thereof.

The vapor generated in the vaporization chamber is discharged into relatively dry air through a discharge port in the vaporization chamber and thence through any suitable tubing. While the water vapor may be injected into the warm air ducts of a hot air system, the apparatus also is particularly adapted to discharge the vapor through a tubular conduit directly into the heated area or heated rooms. The apparatus is therefore well adapted to provide sensitive and efficient humidification for an area heated by a hot water or steam heating system.

It is to be understood that any desired type of liquid may be employed to provide the vapors which are to be diffused. For example, a liquid therapeutic agent, such for example as a glycol may be used, either with or without water and vaporized by the device of the present invention to provide a vapor which may be diffused throughout any desired area.

If water is used as the liquid, steam is generated and is used as the humidifying agent. It has been found also that a portion of the steam generated may be discharged into the furnace stack to aid in cutting down the amount of smoke discharged through the flue.

Having thus described my invention, I claim:

1. A vaporizing apparatus for maintaining a desired vapor content in a gaseous medium, comprising a heat exchanger adapted to extend within a heated portion of a heating unit and having a closed vaporizing chamber therein disposed within the heated portion of the heating unit and provided with a vapor discharge port communicating with the gaseous medium exteriorly of the heated portion of the heating unit, a liquid reservoir mounted exteriorly of the heated portion of the heating unit and adapted to contain a volatile liquid, an absorbent liquid metering member having a portion immersed in the liquid in said reservoir and another portion extending into said vaporizing chamber to meter the liquid from said reservoir at a rate substantially proportional to the rate of evaporation of the liquid from the portion of said member extending into the vaporizing chamber of said heat exchanger, and means to prevent the accumulation of liquid in said vaporizing chamber in excess of the liquid

retained by said absorbent metering member.

2. A humidifying apparatus for maintaining a desired moisture content in the atmosphere of an enclosed space, comprising a heat exchanger adapted to extend within a heated portion of a heating unit and having a closed vaporizing chamber therein disposed within the heated portion of the heating unit and provided with a vapor discharge port communicating with the atmosphere exteriorly of the heated portion of the heating unit, a liquid reservoir mounted on the outside of said heated portion of the heating unit and adapted to contain a quantity of liquid water, an absorbent liquid transfer member having a portion immersed in the water in said reservoir and also having a portion extending into said vaporizing chamber, said member metering the water from said reservoir at a rate substantially proportional to the rate of vaporization of water within said heat exchanger, and means to prevent the accumulation of liquid water in said vaporizing chamber in excess of the liquid water retained by said absorbent liquid transfer member.

3. A humidifying apparatus in accordance with claim 2 and further characterized in that said absorbent member comprises plates having a structure including a plurality of capillary spaces whereby the water is metered to said chamber by capillary attraction through said plates at a rate substantially proportional to the rate of vaporization of water within said heat exchanger.

4. A humidifying apparatus for maintaining a desired moisture content in the atmosphere of an enclosed space, comprising a heat exchanger adapted to extend into a flue of a furnace and having a steam chamber therein disposed within the flue and provided with a steam discharge port to communicate with the atmosphere exteriorly of the flue, a water reservoir mounted on the outside of said flue and adapted to contain a quantity of water, an absorbent plate having a portion adapted to be immersed in the water in said reservoir and also having a portion extending into said chamber, means for maintaining the water within said reservoir at a constant level, said plate metering the water from said reservoir at a rate substantially proportional to the rate of evaporation within said heat exchanger, and means to prevent the accumulation of liquid water in said steam chamber in excess of the liquid water retained by said absorbent plate.

5. A humidifying apparatus for maintaining a desired moisture content in the atmosphere of an enclosed space, comprising a heat exchanger adapted to extend into a flue of a furnace and having a steam chamber therein disposed within the flue and provided with a steam discharge port communicating with the atmosphere exteriorly of the flue, a water reservoir mounted on the outside of said flue and positioned below said steam chamber, and a water absorbent plate having a portion immersed in the water in said reservoir and also having a portion extending into said chamber, said plate metering the water from said reservoir at a rate substantially proportional to the rate of vaporization of water within said heat exchanger, said heat exchanger having an opening at the bottom of said steam chamber and communicating with said reservoir, the bottom of said heat exchanger being above the level of the water in said reservoir whereby condensation within said steam chamber will return by gravity flow to said reservoir.

6. A humidifying apparatus for maintaining a desired moisture content in the atmosphere of an enclosed space comprising a hollow member of heat conducting material having an opening at one end thereof, the closed end portion of said hollow member forming a steam chamber and being adapted to extend into a heated portion of a heating unit, a cover plate for closing the opening end of said hollow member and cooperating therewith to provide a water reservoir positioned exteriorly of the heated portion of the heating unit below said steam chamber whereby water condensation within the latter will return by gravity flow to the reservoir and an absorbent plate positioned within said hollow member and extending from said steam chamber to said reservoir whereby water within the latter is metered to the steam chamber in proportion to the rate of vaporization within said chamber, said hollow member having a steam discharge port adapted to communicate with the atmosphere.

7. A humidifying apparatus for maintaining a desired moisture content in the atmosphere of an enclosed space comprising a hollow member of heat conducting material having an opening at one end thereof, the closed end portion of said hollow member forming a steam chamber having external heat conducting fins and being adapted to extend into a heated portion of a heating unit, a cover plate for closing the open end of said hollow member and cooperating therewith to provide a water reservoir positioned exteriorly of the heated portion of the heating unit and below said steam chamber, means for maintaining the water level in said reservoir below the bottom of said steam chamber whereby water condensation within the latter will return by gravity flow to the reservoir and an absorbent plate positioned within said hollow member and extending from said steam chamber to said reservoir whereby water within the latter is metered to the steam chamber in proportion to the rate of vaporization within said chamber, said hollow member having a steam discharge port adapted to communicate with the atmosphere.

8. A humidifying apparatus for maintaining a desired moisture content in the atmosphere of an enclosed space comprising a hollow member of heat conducting material having an opening at one end thereof, the closed end portion of said hollow member forming a steam chamber and being adapted to extend into a heated portion of a heating unit, a cover plate for closing the open end of said hollow member and cooperating therewith to provide a water reservoir positioned exteriorly of the heated portion of the heating unit and below said steam chamber, means to maintain the water level in said reservoir below the bottom of said steam chamber whereby water condensation within the latter will return by gravity flow to the reservoir and an absorbent L-shaped plate positioned within said hollow member, one end of said L-shaped plate extending into said steam chamber and the other end thereof extending into the water within said reservoir whereby water within the latter is metered to the steam chamber in proportion to the rate of vaporization within said chamber, said

hollow member having a steam discharge port adapted to communicate with the atmosphere.

9. A humidifying apparatus for maintaining a desired moisture content in the atmosphere of an enclosed space comprising a hollow member of heat conducting material having an opening at one end thereof, the closed end portion of said hollow member forming a steam chamber and being adapted to extend into a heated portion of a heating unit, a cover plate for closing the open end of said hollow member and cooperating therewith to provide a water reservoir positioned exteriorly of the heated portion of the heating unit and below said steam chamber, means to maintain the water level in said reservoir below the bottom of said steam chamber, a plurality of plates each positioned within said hollow member and extending from said steam chamber to said reservoir, each of said plates having a structure including a plurality of capillary spaces whereby the water within the reservoir is metered by capillary attraction to the steam chamber in proportion to the rate of vaporization within said chamber, said hollow member having a steam discharge port adapted to communicate with the atmosphere, and means to prevent the accumulation of liquid water in said steam chamber in excess of the liquid water retained by said plates and to permit the return of any water condensation by gravity flow to said reservoir.

10. A vaporizing apparatus for maintaining a desired vapor content in a gaseous medium, comprising a heat exchanger having a closed vaporizing chamber adapted to be placed in heat exchange relation with a heated portion of a heating unit, said vaporizing chamber communicating with the gaseous medium exteriorly of the heated portion of the heating unit, a liquid reservoir mounted out of heat exchange relation with the heated portion of the heating unit and adapted to contain a volatile liquid, an absorbent liquid metering member having a portion immersed in the liquid in said reservoir and another portion extending into said vaporizing chamber to meter the liquid from said reservoir at a rate substantially proportional to the rate of vaporization of the liquid from the portion of said chamber extending into the vaporizing chamber of said heat exchanger, and means to prevent the accumulation of liquid in said vaporizing chamber in excess of the liquid retained by said absorbent liquid metering member.
